UNITED STATES PATENT OFFICE.

FRANCIS J. DOWLING, OF NEW YORK, N. Y., ASSIGNOR OF ONE-HALF TO DANIEL P. CONWAY, OF NEW YORK, N. Y.

SWINGING SANITARY WINDOW-CUPBOARD.

1,212,028.

Specification of Letters Patent.

Patented Jan. 9, 1917.

Application filed March 29, 1916. Serial No. 87,469.

To all whom it may concern:

Be it known that I, FRANCIS J. DOWLING, a citizen of the United States, and a resident of the city of New York, borough of Manhattan, in the county and State of New York, have invented a new and Improved Swinging Sanitary Window-Cupboard, of which the following is a full, clear, and exact description.

10 This invention relates to storage receptacles and has particular reference to devices adapted for connection with and use upon the outside of apartment house windows or analogous places.

15 Among the objects of the invention is to provide improved facilities for the storage of milk, meats and other food products in or adjacent a window whereby the commodities may be easily placed into the receptacle 20 or cupboard and likewise removed therefrom.

25 Another object of the invention is to so arrange or suspend a storage receptacle, of the character indicated, on the outside of a building, that it will not obstruct the light or interfere with the ventilation through the window and which, furthermore, will lie normally in such a position as to be as free as possible from contamination.

30 With the foregoing and other objects in view, the invention consists in the arrangement and combination of parts hereinafter described and claimed, and while the invention is not restricted to the exact details 35 of construction disclosed herein, still for the purpose of illustrating a practical embodiment thereof reference is had to the accompanying drawings, in which like reference characters designate the same parts in 40 the several views, and in which—

Figure 1 is a perspective view of a building showing my improvement suspended adjacent thereto and occupying its normal position against the wall remote from the 45 window; Fig. 2 is a perspective view of the cage portion of the device; Fig. 3 is a perspective view of the box portion of the cupboard indicating the doors open; Fig. 4 is a horizontal sectional view on the line 4—4 50 of Fig. 7; Fig. 5 is a similar view but showing the cupboard swung around for access at or through the window; Fig. 6 is a bottom plan view with the cupboard in the position indicated in Fig. 4; Fig. 7 is a vertical trans- 55 verse section on the line 7—7 of Fig. 4; Fig.

8 is an elevation of a detail, partly in section, on the line 8—8 of Fig. 7; and Fig. 9 is a perspective view of the pull piece detached.

Referring now more particularly to the drawings I show a construction including a box or cupboard proper 10 having a bottom 11, end walls 12, a rear wall 13, and an inclined roof 14. The front 15 of the cupboard is provided with one or more movable doors 16 shown as two in number and mounted upon vertical hinges 17. This cupboard may be of any suitable design or size and fitted with any suitable number or location of transverse and vertical partitions 18 and 19 to provide various compartments within the cupboard.

Adjacent the rear wall 13 and parallel thereto is an inner or false wall 20 of any suitable material, and at 21 is a false roof. 75 These parts 20 and 21 are arranged in close parallel relation to the rear wall and roof, providing an air space, and suitable openings 22 and 23 are provided at the bottom and top of said air space to provide a circulation of air upwardly and forwardly through said space. The shelf 18 may be spaced at the front edge as indicated at 24, and other openings 25 may be provided through the shelf and false wall 20 to facilitate the circulation of air through the storage portions of the receptacle from the air space above described.

Any suitable means may be provided to manipulate the cupboard so as to move it 90 into position at the window for the purpose of access thereto through the window. For this purpose I provide means whereby the cupboard is swung around a vertical axis so as to bring the front walls and doors 95 thereof, which normally are remote from the wall W of the building, around so as to be adjacent the plane of the window sash.

At 26 I show a pair of hinge brackets secured rigidly to the corner of the wall with 100 their eyes 27 arranged in vertical alinement at any suitable distance outwardly from the wall, but preferably lying in the plane of the edge of the wall adjacent the window frame F. Corresponding hinge brackets 28 with vertically alined eyes 29 are secured to either or both ends of the cupboard for co-operation with the brackets 26. I prefer to provide brackets as described for both ends 105 of the cupboard so as to make it easily ap- 110

plicable to either the right or left side of the window. The brackets 26 and 28 are so proportioned and their axes along which they are connected are so located with respect to the cupboard and wall that the cupboard will swing practically against the wall when in normal position, but will permit the front portion of the cupboard to swing well within the window opening when in position 10 to be reached by the person within the building. In other words, the axis 30 around which the cupboard is adapted to swing is preferably arranged at the rear of the vertical longitudinal central plane of the cupboard, whereby the front portion of the cupboard will project well inwardly over the window sill as shown in Fig. 5. In this position, with the window sash S sufficiently raised, the doors 16 may be opened inwardly 20 and the person within the building will have easy access to the interior of the cupboard for the usual purposes.

Any suitable means may be provided to hold the cupboard in its normal open position and also in its position within the window. At 31 I show a hook pivoted at 32 at the bottom of the cupboard and adapted to snap over an L-shaped pin 33 driven into the wall. A spring 34 is connected at the opposite end of the hook 31 and tends to cause the hook to engage the pin and maintain such engagement. One end of the spring is fixed at a point 35 adjacent the front portion of the cupboard. The release of the hook is effected by means of a pullpiece 36 in the nature of a bell crank and having a downwardly projecting part 36^a and a horizontal stop part 36^b. This pull piece is pivoted at 37 upon a slide 38 movable along a 40 keeper 39 secured to the bottom of the cupboard adjacent that front corner thereof nearest the window. The slide is provided with a shoulder portion 38' adapted to abut against the keeper 39 to limit the distance 45 to which the slide may be pulled by the operator when pulling upon the pull piece. The normal position of the pull piece and its relation to the slide are shown best in Fig. 8, in which the stop member 36^b lies against 50 or close to the outer end 38^a of the slide. The force of the spring 34 in holding the hook in engaging position likewise holds the slide with the shoulder 38' spaced from the keeper 39. Draft upon the pull piece by the 55 operator's fingers toward the window is positive, because of the contact between the parts 36^b and 38^a, thereby causing the slide to swing the hook around its pivot to release it from the pin 33. Continued pull 60 in the same direction causes the cupboard to swing around the vertical axis 30 of the hinges until the cupboard approaches its position for access. When the end of the cupboard remote from the operator comes adjacent the edge of the window, the oper-

ator may grasp the same to continue the swinging movement, and during this action the pull piece rides idly up over or upon the window sill, as indicated in dotted lines in Fig. 8.

At 40 is indicated a suitable catch pivoted to the front portion of the bottom of the cupboard and acted upon by a spring 41 connected to the same point 35 as the other spring and adapted to engage over a pin 42 secured to the window sill. A portion of the catch 40 is bent up forming a finger piece 43, whereby it may be easily released when the cupboard is to be swung out again to normal position.

Auxiliary to the hinge connections above described I provide an overhead hanger to insure maximum stability for the suspension means. This hanger comprises a crane composed of an angle member 44 and link 45 having feet co-operating respectively with the outer and inner ends of the cupboard at 46 and 47. The link has an eye 48 connected to the elbow portion of the angle member and the inner end of the angle member is provided with a hook 49 engaging in a fixed member 50, the eye of which is in the same vertical axis as the other hinge members. The crane thus provided serves to steady the cupboard, relieving the main 95 hinges from lateral and endwise tilting strains. Since, however, the axis of the crane coincides with that of the hinges, perfectly free swinging movement of the cupboard around such axis is provided.

While under certain conditions, as above intimated, the supporting and actuating devices may be connected directly to the cupboard or box-like receptacle, it may be preferable to provide a cage such as indicated 105 at Fig. 2 (see Fig. 2) for these connections. As shown herein, the cage is of skeleton construction and provided with vertical angle members 52 into which the corners of the receptacle are fitted, and also front and rear 110 bottom angle members 53 into which the front and rear longitudinal bottom edges of the cupboard box are fitted. A rim 54 extends around the upper portion of the cage and a pair of cross bars 55 connect the lower 115 corners of the cage. As shown, the angle members 46 and 47 constitute the upper ends of a U-shaped reinforcement bar 56 extending longitudinally along the central part of the bottom of the cage and thence upwardly 120 at the ends. The hinge brackets 28 may be connected to the corner angles 52 at the rear portion of the cage. Likewise the hook and catch devices 31 and 40 may be connected to the bottom members of the cage.

I claim:—

1. In a storage receptacle of the character set forth, the combination of a cupboard proper, hinge connections for one end thereof for securing it in position adjacent one

side of a window to swing around a vertical axis against the wall or in the opposite direction so as to project well within the window opening, an automatically operated hook carried by the cupboard and coöperating with the wall to hold the cupboard in normal position remote from the window, a pivoted pull piece connected to the hook to release the same from holding position and providing means for swinging the cupboard into the window, and means to hold the cupboard in the position last mentioned.

2. In combination, a storage receptacle, a pair of hinges connecting one end of the receptacle to the edge of the wall adjacent the window opening providing for swinging of the cupboard around a vertical axis either adjacent the wall at one side of the window or well within the window opening, automatic means to hold the cupboard in either of said positions, and auxiliary hanger means coöperating with said hinges to relieve the hinges from lateral and side tilting strains, said hanger means including a fixed bracket having an eye above and in alignment with the axes of the hinges, an angle member connected at the one end to one end of the cupboard and having a hook at its other end pivoted in said eye, the angle member being directly above the center of the opposite end of the cupboard, and a link connected to the latter mentioned end of the cupboard and extending directly up into engagement with the angle of the angle member.

3. The combination of a cupboard, a pair of hinges connecting one end of the cupboard to the edge of the wall adjacent the window opening and providing for the swinging of the cupboard around against the wall or into the window, overhead hanger means including an angle member and a link connected to the angle of the angle member in the vertical longitudinal central plane of the cupboard and a hinge member to which the angle member is pivoted on an axis coinciding with the axis of the hinges and at one side of said plane, and means to hold the cupboard in either position to which it may be swung around said axis.

4. In a device of the character set forth, the combination of a cage comprising a plurality of vertical corner angle members, front and rear longitudinal bottom edge angle members, all of said angle members having their open sides directed inwardly, a U-shaped reinforcing bar coöperating with the aforesaid angle members midway between the front and the rear of the cage, a box-like structure fitted into the cage within the open sides of the angle members aforesaid, suspension means for the box connected to the upper ends of said bar, and catch devices connected to the cage and serving to hold the same in open or closed position.

FRANCIS J. DOWLING.
